UNITED STATES PATENT OFFICE.

HARRY SCHREIBMAN AND LOUIS GOLDBERG, OF BROOKLYN, NEW YORK.

DESIGN FOR A LIGHTING FIXTURE.

Application filed June 9, 1928. Serial No. 27,069. Term of patent 3½ years.

To all whom it may concern:

Be it known that HARRY SCHREIBMAN and LOUIS GOLDBERG, both citizens of the United States, and residents of New York city, borough of Brooklyn, in the county of Kings and the State of New York, have invented a new, original, and ornamental Design for a Lighting Fixture, of which the following is a specification, reference being had to the accompanying drawing, forming part there-

of, in which the figure is a perspective view of a lighting fixture embodying the invention.

We claim:

The ornamental design for a lighting fixture, as shown.

Dated, New York city, June 1st, 1928.

HARRY SCHREIBMAN.
LOUIS GOLDBERG.
